ROCK DRILLING MECHANISM

Filed Dec. 15, 1922

Elmer G. Garber Inventor:

Horace H. Goldsmith

attorney.

UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

ROCK-DRILLING MECHANISM

Application filed December 15, 1922. Serial No. 607,035.

My invention relates to rock drilling mechanisms, and more particularly to the cleansing fluid supply devices for such mechanisms.

An object of my invention is to provide an improved rock drilling mechanism. Another object of my invention is to provide an improved rock drilling mechanism having improved cleansing fluid supply means. A further object of my invention is to provide improved holding means for the cleansing fluid supply tubes of rock drilling devices. Other objects and advantages of my invention will hereinafter more fully appear.

In the accompanying drawings I have shown for purposes of illustration one form which my invention may assume in practice.

In these drawings,—

Fig. 1 is a central vertical longitudinal section through a rock drilling mechanism in which the illustrative embodiment of my invention is incorporated.

Fig. 2 is an enlarged sectional detail view, and is taken on the section line 2—2 of Fig. 1.

In the particular embodiment of my invention which I have elected to show for purposes of illustration, the same is incorporated in a rock drilling device which is generally indicated 1 and comprises a cylinder 2 in whose bore 3 a piston 4 having a striking bar 5 is reciprocable. Rotation mechanism of a well known form is provided and includes a ratchet controlled rifle bar 6 mounted in a member 7 at the rear end of the cylinder 2 and a rotatable chuck mechanism generally designated 8 and having splines 9 cooperating with suitable longitudinal grooves in the striking bar 5. A hollow drill steel 10 is received within the chuck.

Mounted at the rear end of the drill cylinder are a pair of tubes, the inner of which, 11, is adapted to conduct water to the bore of the hollow drill steel 10, while the outer, 12, conducts air. It will be noted that herein the tube 11 projects a substantial distance into the steel, while the tube 12 terminates just short of the steel, although it will be clear that other arrangements may be used if desired. In a member 13, which is the extreme rear member 50 of the drilling mechanism 1, a socket 14 is

formed and with this socket a passage 15, controlled by a valve 16 which may also be the throttle valve for the motor, communicates. Threaded into the socket 14 is a combined gland plug and liquid connection member 18. This member at its forward end, which is externally threaded, is provided with a recess 19, while at its rear end it is similarly provided with an internal recess 20 and external threads 21. The front end of a liquid connection 22 projects into the recess 20 and a clamping member 23 cooperates with the threads 21 to hold the connection in place. A strainer 24 is arranged within the recess 20 to prevent the passage of harmful material into the tube 11 and so to prevent possible plugging thereof. The tube 12 at its rear end is surrounded by a sleeve 26 which is welded onto the tube and this sleeve and the tube proper are traversed by passages 27 which communicate with the front end of the recess 14 and so receive a supply of air through the passage 15 when the valve 16 is in the proper position. The tube 11 has fixed thereto a collar carrying sleeve member 28 and at opposite sides of a collar 29 on this member resilient washers 30 and 31 are arranged. It will be noted that when the member 18 is assembled in the member 13, the rear end of the tube 12 serves as an abutment member and that the sleeve member 28 and the washers 30 and 31 are housed entirely in the recess 19. It will be observed, moreover, that as the member 18 is screwed home, the washers 30 and 31 will be compressed and so the parts will be tightly and yet not entirely rigidly clamped in assembled relation. The washers will of course prevent any leakage of liquid to the air spaces. It will further be noted that the recesses 20 and 19 are interconnected by a smaller bore 32 and the rear end of the tube 11 projects into this bore into communication with the liquid supplied through the strainer. As the particular valve mechanism employed does not relate in anywise to my invention herein, I have simply shown such a mechanism in elevation at 33. No further description of the operation of this mechanism seems nec-

essary, it being clear that concentric streams of air and water will flow through the tubes 12 and 11 when the valve 16 is properly operated and water is supplied to the recess 20.

5 While I have in this application specifically described one form which my invention may assume in practice, it will be understood that this form of the same is shown for purposes of illustration and that the invention 10 may be modified and embodied in other forms without departing from its spirit or the scope of the appended claims.

What I claim as new and desire to secure by Letters Patent is:

15 1. In a cleansing fluid mechanism for a hollow drill steel, a pair of concentric longitudinally arranged tubes for conducting liquid and gaseous cleansing fluid to said steel, a mounting for said tubes comprising 20 a rear head member having a recess, a flange on each of said tubes, resilient packing means in said recess cooperating with said flanges to provide a yielding mounting for said tubes including a packing washer surrounding the 25 inner tube and seating against the flange on said outer tube and closing the end of the same, a gland plug adjustably mounted in said recess to compress said packing means and hold said tubes in position, and means 30 for supplying fluid to said outer tube comprising a passage through said head member leading to said recess forwardly of the end of said gland plug, and means for admitting fluid laterally from said recess into 35 the bore of said outer tube.

2. In a cleansing fluid mechanism for hollow drill steels, the combination specified in claim 1 wherein said passage in the head member is connected to a source of gaseous 40 cleansing fluid, and a connection to said gland plug for supplying cleansing liquid under pressure to said inner tube.

In testimony whereof I affix my signature.
ELMER G. GARTIN.
